EDWIN S. PHILIPS, OF KENNETT SQUARE, PENNSYLVANIA.

CONTACT MAKER AND INTERRUPTER FOR IGNITION SYSTEMS.

1,129,445.

Specification of Letters Patent. Patented Feb. 23, 1915.

Application filed June 4, 1914. Serial No. 842,850.

To all whom it may concern:

Be it known that I, WILLIAM C. BRINTON, Jr., a citizen of the United States, residing at Manoa, county of Delaware, and State of Pennsylvania, have invented a new and useful Improvement in Contact Makers and Interrupters for Ignition Systems, of which the following is a full, clear, and exact description, reference being had to the accompanying drawings, which form a part of this specification.

The object of my invention is to provide an improved means for opening and closing the primary circuit in a single spark ignition system for automobiles.

The nature of the invention will be understood by reference to the accompanying drawings, which show several preferred embodiments of my invention and in which—

20 Figure 1 is a diagram of the electrical connections of an ignition system to which my improved contact maker is applied. Fig. 2 is vertical section through the axis of the shaft which actuates the contact maker. 25 Figs. 3, 4 and 5 are detail views, in side elevation, of three different contact makers embodying my invention. Fig. 6 is a plan view of the contact maker of Fig. 5.

I will first refer to the diagram, Fig. 1, in 30 which *a* represents the battery or other source of energy. *b* is the primary circuit including the coil *c* for engaging the coil *e* of the secondary circuit *d*. The secondary circuit *d* is connected at one end to the frame *f* of 35 the engine for a ground end and extends through the coil *e* to the common terminal post *g*, which, through the rotating distributor conductor *h*, is successively connected with the binding posts 1, 3, 4 and 2, which 40 are respectively connected with the spark plugs of the several cylinders 1', 3', 4' and 2' and the engine. *i* is the usual condenser across the primary circuit. The contact maker embodying my invention is interposed in the primary circuit *b* and is designated by the numerals 14, 22, 26, 35.

The contact maker is shown as connected with a shaft 10, which may either be the cam shaft or a drive shaft having the same rate 50 of rotation as the cam shaft. Collars 11, 12 are fixed upon the shaft to prevent relative longitudinal movement between the shaft and the bottom of the casing 13. This casing may be held from rotation by any suitable means. The contact-maker shaft 14 is

located above and axially in line with the shaft 10. It is preferred to connect shafts 10 and 14 through a governor 18. Any known type of governor may be employed, and as the governor forms no part of my invention it is unnecessary to set it forth in detail.

Within and secured to the casing is a floor or frame 15 the center of which is shaped to form a bearing for the shaft 10. The upper end of the shaft 14 carries a head of insulating material 16, to which is secured the distributor conductor plate *h*. The end of the casing is closed by a cap of insulating material 17, which carries the common terminal post *g* and the binding posts 1, 2, 3 and 4, hereinbefore mentioned; the secondary circuit being closed successively through the several binding posts as the shaft 14 revolves.

The parts hereinbefore described form no part of the present invention and are set forth in order that the relation of the invention to the ignition system as a whole may be understood.

To the shaft 14 is secured a collar 21 carrying radially extending trip pins 22. Of the several embodiments of my invention I will first refer to that shown in detail in Fig. 3. On a bracket 23 secured to the frame 15 is a bell-crank lever 24. Secured along one face of one arm of the lever 24 is a flat spring 25 which extends beyond the end of the lever and carries a head 26 which is virtually a continuation of the lever. The end of the head is beveled to form a cam face in line of travel of the pins 22.

A stop 27 prevents the lever 14 from moving in a direction opposite to the normal direction of travel of the pins 22, but in the event of the reverse movement of the pins, the head 26 will move independently of the lever, due to its spring connection therewith, until the actuating pin overrides the head 26, whereupon the spring 25 will immediately return the head to normal position.

The lever 14 is normally held against the stop 27 by means of a spring 28.

The opposite arm of the lever 24 has an extension 29, which may abut against the end of the lever. A spring 30 connects the lever and its extension and permits the extension to move relatively to the lever only in one direction.

Another bell crank lever 31 is pivoted on a bracket 32 secured to the frame 15 and is held, by means of a spring 33, against a stop 34. The end of the lower arm of this lever is close to the outer end of the extension 29 of the lever 24, and both ends present opposing beveled faces. The terminals of the primary circuit *b* are connected respectively to a contact 36 on the lever 31 and to a contact 35 supported on the spring 37 (see Fig. 6).

In the rotation of the cam shaft, the pins 22 strike the head 26, thereby tilting the lever 24 and causing the beveled end of its extension 29 to contact with and slide upon and beyond the beveled end of lever 31. This operation causes the upper end of lever 31 to dip toward and against contact 35 and momentarily close the primary circuit *d*. At this time the shaft 14 has turned into such position that the outer end of the distributor conductor *g* is in proper relation to one of the binding posts 1, 2, 3 and 4, so that immediately upon the breaking of the primary circuit between contacts 36 and 35 and the consequent energizing of the secondary circuit, current is permitted to pass to the spark plugs of the cylinders 1', 2', 3' or 4'. As soon as the lever 31 has so closed the primary circuit, the extension 29 moves beyond lever 31, which is at once returned by the spring 33.

On the return movement of the lever 24 under the impulse of spring 28, the extension 29 again engages lever 31 and tends to move it in the direction opposite to that in which it was moved in the forward movement of lever 24, but the stop 34 prevents such movement of lever 31. The spring 30, however, allows the extension 29 to lag behind until the body of the lever 24 has nearly reached its normal position, whereupon the extension 29 snaps over and beyond the lever 31, without imparting any movement thereto.

In the modification shown in Fig. 4, the corresponding parts are similarly designated, except in the following particulars. For the extension 29 is substituted an extension 40, which, while supported, like extension 29, on a spring 41 secured to the lever 24, is spaced from, instead of abutting against, the end of lever 24. Further, the contacting ends of said extension and lever 31 are not provided with opposite beveled faces. That is, the contacting ends are beveled, but they are beveled on the non-adjacent faces of the members 40 and 31.

In the operation of this embodiment of my invention, the lever 31 does not begin to tilt, as in the construction of Fig. 3, as soon as the extended end of lever 24 contacts with lever 31, but the first operation is to arrest the downward movement of the extension 40. The latter is held stationary

until the tension of spring 41 (which of course increases as its supporting arm moves down) overcomes the tension of spring 33, whereupon the extension 40 snaps beyond the lever 31 and in such movement tilts the lever 31 and causes its contact 36 to momentarily engage contact 35. In the return movement of the lever 24, the operation is the same as that of the construction of Fig. 3; that is, extension 40 moves against, and then snaps over, the lever 31 without imparting to it any movement.

In the construction shown in Figs. 5 and 6, the contact-making lever 31 and the means for immediately actuating it are the same as in Fig. 4, but for lever 24 a somewhat different construction is adopted.

50 is a bar slidable vertically in a two-armed bracket 51. The bar 50 has an independently movable cam head 52 (similar to head 26) supported on the spring 53, the upper arm of the bracket 51 being slotted to allow the head to move backwardly in case it should be carried in that direction by one of the pins 22. One face of the bar 50 is cut away and recessed to receive the spring 53. A coil spring 54 surrounds the bar 50 and is confined between the lower arm of the bracket 51 and a pin 55 secured to the bar. This spring normally holds the cam head 52 in line of travel of the pins 22. To the lower end of the bar 50 is secured an arm 56 carrying a spring 57 and a head or extension 58. The parts 56, 57 and 58 correspond to the parts 24, 41 and 40 of Fig. 4 in structure and mode of operation; the only difference being that the arm 56 moves vertically, or at right angles to the direction of its extension, instead of pivotally.

Having now fully described my invention, what I claim and desire to protect by Letters Patent is:

1. In a contact device, a movable member normally held in inoperative position, a cam carried thereby through which it is actuated, a second movable member having a part thereof in line of movement of the first member at one point in the latter's advance movement, whereby the second member will be advanced by the first member to close the circuit, a tension device adapted to immediately return the second member when the first member has advanced beyond it, and means to render the first member inoperative, in its return movement, to actuate the second member to close the circuit.

2. In a contact device, a movable member, a cam carried thereby through which it is actuated, a second movable member having a part thereof in line of movement of the first member at one point in the latter's advance movement, whereby the second member will be advanced by the first member to close the circuit, tension means adapt-

ed to return both members when the first member has passed beyond the second member, a stop limiting the movement of the second member, a stop limiting the movement 5 of the first member, and means to render the first member inoperative, in its return movement, to actuate the second member to close the circuit.

3. In a contact device, two movable members, tension means and stops therefor, co-operating means carried by the two members whereby the advance movement of the first member against tension causes an advance movement of the second member against tension, means to close the circuit adapted to be operated in the advance movement of the second member, and means to render the first member inoperative, when returned, to actuate the second member to close the circuit.

4. In a contact device, a movable member adapted to be primarily actuated, a second movable member, parts carried by the two members adapted to engage in the advance movement of the first member to cause an advance movement of the second member, means to close the circuit adapted to be operated in the advance movement of the second member, and means to render the first member inoperative, on its return movement, to actuate the second member to close the circuit.

5. In a contact device, a movable member adapted to be primarily actuated, a second movable member, parts carried by the two members adapted to engage in the advance movement of the first member to cause an advance movement of the second member, means to close the circuit adapted to be operated in the advance movement of the second member, and means coöperating with the first member permitting said engaging part carried thereby to yield relatively to the second member in the engagement of said parts on the return movement of the first member.

6. In a contact device, a pivoted lever, a stop limiting its movement, a head on said lever having a cam face through which the head is normally operated in one direction and an abutting face through which the head is operable in the opposite direction, a second lever and a stop limiting its movement, the second lever having a part thereof in line of movement, tension means to return both levers against their stops when moved away therefrom, of the first lever at one point in the latter's advance movement whereby in the forward movement of the first lever the second lever will be positively advanced to close the circuit, and means to render the first member inoperative, on its return movement, to actuate the second member to close the circuit.

7. In a contact device, a movable member

adapted for primary actuation, a second movable member, said members having parts with opposing faces adapted successively to engage and slide upon one another and disengage in the advance movement of the first member, thereby positively moving the second member into circuit-closing position, tension means to return said members to normal position, and means permitting the contacting part of the first member to yield relatively to the second member in the return movement of the first member, thereby avoiding actuation of the latter to again close the circuit.

8. In a contact device, a pivoted lever adapted for primary actuation, an extension of said lever, a spring on said lever supporting said extension, a second pivoted lever adapted to be actuated by said extension, in its movement in one direction, to close the circuit, and a tension device and stop for the second lever.

9. In a contact device, a lever pivoted between its ends, a head on said lever having a cam face through which it is normally operated in one direction, said head abutting against the lever and imparting thereto its movement in a forward direction, a spring supporting said head and permitting it to move independently of the lever in the other direction, a pivoted circuit closing and opening lever adapted to be engaged and moved into circuit closing position by the first lever in the latter's forward movement, tension means to return both levers, and stops limiting the return movement of both levers.

10. In a contact device, a pivoted bell-crank lever adapted for primary actuation, a tension device tending to hold said lever in inoperative position, a stop limiting the movement of said lever by said tension device, a spring-supported extension on one end of said lever, a second pivoted bell-crank lever, one arm of which extends under and in line of movement of said extension, whereby the extension, in the advance movement of the first lever, will tilt the second lever into position to close the circuit, a tension device arranged to return the second lever to inoperative position after the extension has passed beyond it, and a stop arranged to both limit the movement of the second lever by said tension device and to prevent the actuation of the second lever by said extension in the return movement of the second lever.

11. In a contact device, a primary circuit, a secondary circuit in which a current is induced by the make and break of the primary circuit, two movable members one of which is adapted to actuate the other to move the latter into position to close the primary circuit, means to return the second member into position to open the primary circuit when the first member has moved beyond

the second member, and a circuit breaker in the primary circuit adapted to open the primary circuit in the event of abnormal maintenance in circuit closing position of the second member.

In testimony of which invention, I have

hereunto set my hand, at Philadelphia, on this 1st day of June, 1914.
